MARKING DEVICE

Dennis W. Smith, Chicago, Ill., assignor to Col-
borne Manufacturing Company, Chicago, Ill.,
a corporation of Illinois

Application January 6, 1939, Serial No. 249,609

2 Claims. (Cl. 101—3)

This invention relates to hand-operated, mechanically-supported marking devices particularly designed for use in impressing insignia on plastic sheets such as the upper crust for pies. 5 The construction is adaptable for making an impression on dough discs as the discs pass from a dough roller of a pie machine along an inclined conveyor or slide. These discs at the time of receiving the impression may be at different positions on the inclined support either laterally or longitudinally thereof, and hence it is desirable to provide a mounting for the marker permitting more-or-less universal movement of the marker.

Accordingly it is among the purposes of the invention to provide a marking device suitable for the particular conditions mentioned. It is also an object of the invention to provide an improved resilient and adjustable mounting for the marker tending to hold it in some normal clear- 20 of-the-work position in connection with an arrangement whereby the marker may be swung entirely out of the way when not in use.

The objects of the invention are accomplished by a construction as illustrated in the drawing, wherein:

Figure 1 shows a perspective view of the marking device and indicates broken away an inclined guide chute for articles operated upon.

Fig. 2 shows the marker in longitudinal section.

Fig. 3 shows a sectional detail taken on the line 3—3 of Fig. 2.

Fig. 4 is a sectional detail taken on line 4—4 of Fig. 2.

The essential elements of the marking device include a supporting base bracket. This bracket is made extensible and includes an upright hollow post within which is slidably supported a post extension element movable with a spring carrier. The marker is carried at the outer end of telescoping elements suspended by a spring from the carrier and pivotally connected with the post extension. By this arrangement the necessary freedom of motion of the marker is provided against resilient reaction which tends to hold the marker normally clear of the work.

As shown in Figs. 1 and 2, the extensible bracket base consists of two parts 1 and 2 which are connected together at the location of slot 3 in part 1 by means of the wing nut 4 engaging the threaded stud 6 carried by part 2. The part 2 of the bracket also has a screw clamp 6 for engagement with a supporting flange on a dough rolling or pie making machine. The bracket element 1 has welded or brazed thereto a vertical tube 1 forming a hollow post in which is adjust-

ably mounted a tubular element 8 at the top of which is a jointed construction 9 for carrying telescoping tubular arms 10 and 11. A marking head 12 is pinned at 13 to the outer end of tube 11. The marking head is arranged to support 5 against rotation detachable type-carrying members 14, and also carries an operating handle 16. Tube 11 is slotted at 16 to receive the head of a screw 17 carried by tube 10. The slot 16 is wider than the screw in order to allow for a 10 limited rotary motion of tube 11 on tube 10. The head of screw 17 is connected by a spring 18 with a bent rod 19. The lower end of rod 19 is threaded for the purpose of adjustably engaging a collar 20 surrounding post 7 and may be 15 clamped to this collar by the lock nut 21. The lock nut serves to prevent the rod from rotating in its support.

Collar 20 and the extension 8 of post 7 are connected together by a screw 22 passing through 20 a vertical slot 23, Fig. 1, in tube 7. By means of this screw the telescoping members 7 and 8 may be clamped together in the desired adjusted position for determining the normal height of the marker above the inclined chute 24, Fig. 1, 25 for the work. A dough disc is indicated at 25 on the chute.

The joint 9 is a hinge, one member 24 of which is pinned to tube 10. The other member 25 has an annular groove 26 in which loosely fits a screw 30 27 carried by post extension 8 for the purpose of allowing free rotation but retention of member 25 within the extension 8.

A moved position of the device is indicated by broken lines in Figure 1 which serve to show 35 the telescoping members 10 and 11 extended and the type carrier turned.

In operating the device, impressions are made through use of the handle 16, whereby the type-carrying tube 11 is slid outwardly and turned 40 while both tubes are swung downwardly from the hinge to make the impression.

I claim:

1. A marking device of the nature specified comprising a bracket carrying an extensible telescoping post construction, clamping means for the telescoping members of the post, said clamping means having mounted thereon a spring carrier, a swivel hinge mounted at the top of said post and carrying a pair of telescoping members 50 capable of relative axial motion, a stamping device carried by one of said last mentioned telescoping members, and a spring connecting the spring carrier with said last mentioned telescoping members. 55

2. A marking device of the nature specified comprising a supporting base and a post supported on said base, a swivel hinge mounted at the top of said post and carrying a pair of telescoping members mounted for a relative axial movement, a stamping device carried by one of said telescoping members to move therewith in an axial direction relative to the other telescoping
- 5.

member, means providing for a limited rotary motion of said stamping device, and a support for said telescoping members including resilient means arranged for resisting downward and lateral motion of the telescoping members on the swivel hinge.

DENNIS W. SMITH.
